KNOCKDOWN DRAWER

Bayard E. Richardson, Grand Rapids, Mich.

Application May 26, 1930, Serial No. 455,525
Renewed March 24, 1933

7 Claims. (Cl. 20—92)

This invention relates to a drawer of knock-down readily assembled form and which, when assembled, is greatly strengthened and reinforced at its corners by reason of the metal connecting members utilized at the corners for tying the side and end members of the drawer together and for holding them against disarrangement or separation.

The present invention is primarily concerned 10 with an exceedingly simple and practical construction of drawer, wherein the parts thereof are very readily and easily machined and in which the assembly may be accomplished in the factory or at the place of shipment of the article 15 of furniture in which the drawers are to be installed. The invention is directed to a novel, economical and practical structure for attaining the ends stated, at the same time effecting a very material strengthening and reinforcing of 20 the drawer structure.

An understanding of the invention may be had from the following description, taken in connection with the accompanying drawing, in which,

Fig. 1 is a perspective view of a drawer made 25 in accordance with my invention.

Fig. 2 is a perspective view of a corner made in accordance with my invention.

Fig. 3 is a fragmentary perspective view showing the formation at the ends of the sides and 30 ends of the drawer with which the corner tie member shown is used.

Fig. 4 is a fragmentary horizontal section through one corner of a drawer after the parts have been assembled, and

Fig. 5 is a perspective view showing a different 35 form of metallic tie construction which may be used in the place of that shown in Fig. 2.

Like reference characters refer to like parts in the different figures of the drawing.

The drawer includes the usual vertical sides 40 1, and ends 2 which, at their inner sides and near their lower edges, are horizontally grooved, making grooves 3 for the reception of the side and end edges of a bottom 4 which is held in 45 place when the two sides and two ends of the drawer are connected together.

Each end 2 of the drawer is of greater thickness than the sides 1, and each end at its inner side and at each end is cut away making a right 50 angle vertical recess 5; and in line with the vertical sides of said recess, narrow grooves 6 and 7 are cut, as shown in Fig. 3, which lie at right angles to each other. It is evident that in sawing the end member 2 of the drawer to remove the 55 material in making the right angle recess 5,

a continuation of the saw cuts beyond where they meet provides the grooves 6 and 7.

Each side 1 at each end thereof and at its inner side is provided with a vertical groove 8 which lies substantially in the same plane with the inner side of the adjacent end 2 of the drawer when the parts are assembled. In addition each of the side members 1 of the drawer at its outer side and at each end has a vertical rabbet 9 made therein, the depth of which is the same as the thickness of the metal from which the tie members used at the corners are made. Likewise the width of the grooves 6, 7 and 8 are substantially the same as the thickness of such metal.

The metal tie member used at each corner of the drawer may be that illustrated in Fig. 2.

As there shown a length of flat metal is bent longitudinally to provide two legs 10 and 11 at right angles to each other, the free edge portions of which are each turned at right angles to make vertical terminal lips 12.

One of the legs, such as 10 of the member, near the lower end thereof, has a notch 13 cut away so designed that the upper side of the notch will come against the upper side of the drawer bottom 4 when the tie member is inserted and driven in place.

At the vertical corner, where the legs 10 and 11 join, tongues 14 and 15, respectively are struck from the legs 11 and 10, respectively, and, are in position in the planes of said legs 10 and 11.

Each of these tongues at its outer free vertical edge is cut downwardly and inwardly, as indicated at 16, making each tongue in effect a tooth which freely permits the downward movement of the tie member into place, but which will bite or

graze into the wood from which the sides and ends 1 and 2 are made to prevent any upward movement of such tie member after it has been inserted.

The assembly of the sides and ends and bottom is simple. The bottom having been located in the grooves 3, at each corner of the drawer one of the metal tie members illustrated in Fig.

2 is inserted downwardly, the flanges 12 entering the groove 8 and the rabbet 9 and the tongues 14 and 15 entering the grooves 6 and 7, while the leg 10 lies between one side of the recess 5 and

the inner side of the side 1 of the drawer, and leg 11 between the other side of the recess 5 and the vertical end of the drawer, all as fully shown in Fig. 4.

And once the tie member at the corner is in place the toothed tongues 14 and 15 prevent disassembly as described.

A different form of metallic tie construction may be used, like that shown in Fig. 5. It con-

- sists of two members, each made of flat metal into Z-bar form, having a web 17 and flanges 18 and 19 turned in opposite directions from the opposed vertical edges of the web. Each of the 5 webs 17 is also provided with inwardly struck retaining tongues 20, and at a lower corner of one of the members a notch 13a is made for the same purpose as the notch 13 in the construction illustrated in Fig. 2.
- 10 This construction is used in substantially the same manner, the flanges 18 being equivalent to the lips 12 previously described, the webs 17 equivalent to the lips 12 previously described, and the flanges 19 equivalent to the tongues 14 and 15 15 except for the toothed retaining feature applicable to the tongues, which, in the structure shown in Fig. 5, is taken care of by the retaining tongues 20.
- With this construction the parts, including the 20 sides, ends and bottom of a drawer, may be fabricated in large quantity production and the metallic tie members separately produced. The drawers which are to be used, may be assembled after they have reached their destination. The 25 assembly is made readily without the use of skilled labor and the drawer produced is one very much strengthened and reinforced at the corners where the vertical metallic tie members are located. The invention is defined in the appended claims and is to be considered comprehensive of all forms of structure coming within their scope.
- I claim:
- 30 1. A construction having a vertical side and end, said end being vertically rabbeted at one end and inner side thereof to receive the end of the side of the drawer, said end at the corner of said rabbet being provided with vertical slots, and said side adjacent its end and at its inner 35 side being provided with a vertical slot and at its outer side with a vertical rabbet, and metal connecting means received in said slots and rabbets on the side and end, and between the side and end for securing said side and end together 40 against separation.
2. Vertically disposed tying means to connect the sides and ends of drawers together at their corners, comprising sheet metal webs located at an angle to each other, said webs at their 45 free vertical edges having flanges turned inwardly toward each other, said webs joining at their opposite vertical edges and having parts extending therefrom in prolongation of each web, said parts lying in vertical planes at an angle to each other.
- 50 3. Vertically disposed tying means to connect the sides and ends of drawers together at their corners, comprising sheet metal webs located at right angles to each other, said webs at their
- free vertical edges having flanges turned inwardly toward each other at right angles to the webs, said webs joining at their opposite vertical edges and having parts extending therefrom at right angles to one of said webs and substantially in the plane of the other web and at right angles to each other. 55
4. In a drawer construction, vertical ends each of which at each end thereof and at its inner side is formed with a vertical right angle recess or rabbet and with vertical grooves having sides in the same planes with the sides of said rabbet, said grooves being located at right angles to each other at the corners of said rabbet, drawer sides each having an end portion formed with a vertical groove at its inner side a short distance from each end of the side of the drawer and with a vertical rabbet at its outer side at the end of the drawer, and metal tie means comprising webs located between the sides of the rabbets in said ends of the drawer, and the ends of the sides of the drawer, and the inner end portion of the inner sides of said sides of the drawer, said webs having integral flanges received in the grooves at the inner sides of the 60 sides of the drawer and in the rabbets at the outer sides thereof, and parts extending at right angles from the webs into said grooves in the ends of the drawer for securely connecting said sides and ends of the drawer together. 65
5. A construction containing the elements in combination defined in claim 4, combined with means on said metallic tying means permitting downward insertion of the metal tying means into said grooves and rabbets but engaging against the parts of the drawer and biting thereinto to prevent upward movement of said metallic tying means. 70
6. A metallic tie for the corners of drawers comprising, a single vertical length of flat metal bent longitudinally midway between its vertical edges to provide two webs located at right angles to each other, each of the free vertical edge portions of said webs being bent inwardly substantially at right angles to its web to form flanges, 75 and each of said webs adjacent where it joins the other having a plurality of tongues struck therefrom and lying in the plane of the other web, said tongues being disposed in planes at right angles to each other and in staggered relation, for the purposes described. 80
7. A construction containing the elements in combination defined in claim 6, each of said tongues at its outer free edge being inclined downwardly and inwardly at an angle to the 85 vertical. 90
